AUTOMOBILE WHEEL COVER

Fred L. Hudson, Jr., Fayetteville, N.Y., assignor to
Chrysler Corporation, Highland Park, Mich., a corpora-
tion of Delaware

Application November 3, 1959, Serial No. 58,195

Term of patent 7 years

(Cl. D14—30)

Fig. 1 is a front elevational view of an automobile wheel cover showing my new design;

Fig. 2 is a sectional view taken on the line 2—2 of Fig. 1; and

Figs. 3 and 4 are sectional views on an enlarged scale, taken respectively on the lines 3—3 and 4—4 of Fig. 1; and

Fig. 5 is a fragmentary perspective view of the automobile wheel cover.

The essential features of my design reside in the por-
tions shown by means of full lines in the drawing.

I claim:

The ornamental design for an automobile wheel cover, substantially as shown and described.
